GOLF CLUB HEAD

Harold Edward Swash, 5 Bushby's Park,
Formby, Lancashire, England

Filed Nov. 17, 1972, Ser. No. 307,440

Term of patent 14 years

Int. Cl. D21—02

U.S. Cl. D34—5 GH

FIG. 1 is a front view of a golf club head according to my design;

FIG. 2 is a plan view of a right handed golf club head in accordance with FIG. 1;

FIG. 3 is a plan view of a left handed golf club head in accordance with FIG. 1;

FIG. 4 is a rear view of a right handed golf club head in accordance with FIG. 1;

FIG. 5 is a rear view of a left handed golf club head in accordance with FIG. 1;

FIG. 6 is a view taken along the lines IV—IV of FIG. 2 or FIG. 3;

FIG. 7 is a perspective view of a right handed golf club head; and

FIG. 8 is a perspective view of a left handed golf club head.

I claim:

The ornamental design for a golf club head, substantially as shown and described.
